UNITED STATES PATENT OFFICE.

ELIAS E. RIES, OF NEW YORK, N. Y.

MOTOR-SKATE.

1,150,966.

Specification of Letters Patent. Patented Aug. 24, 1915.

Application filed March 6, 1906, Serial No. 304,453. Renewed October 3, 1914. Serial No. 864,942.

To all whom it may concern:

Be it known that I, ELIAS E. RIES, a citizen of the United States, and resident of New York, in the county of New York and State of New York, have invented certain new and useful Improvements in Motor-Skates, of which the following is a specification.

My invention relates to improvements in the construction of the frame and operating mechanism of the general form of skate previously invented by me and described in my application for patent filed March 14th, 1906, Serial No. 306,073, and renewed October 3, 1914, as Serial No. 864,943, (the subject-matter of which originally formed the basis of an earlier application for Letters Patent for my said invention, filed August 20, 1898, Serial No. 689,144) wherein I have described a skate in which the propelling power is derived from a depressible foot-plate mounted on a suitable supporting frame connecting front and rear wheels, said plate being connected to means for equalizing the extent of downward movement of all parts of the foot-plate and the driving mechanism being operatively connected with said plate.

My present improvements relate more particularly to the supporting frame and to the connection between said frame and the depressible foot-plate.

The main objects of my invention are, first:—to so construct the supporting frame that the foot-plate may operate entirely above the same, to avoid the necessity of making different sized frames for different widths of shoes, while still keeping the center of gravity at a low point: second,—to so construct the entire frame and skate operating mechanism carried thereby, that they will be contained within the width of the foot-plate of the skate or the foot of the skater or pedestrian, so as to prevent interference of one skate with the other and to permit the skate to be operated over a comparatively narrow path or against a curb or other obstruction: third,—to provide a construction whereby the skate frame is materially stiffened and rendered more rigid, while at the same time reducing its weight, thereby enabling me to use a given weight of material to the greatest mechanical advantage, and to considerably lighten, and increase the ease of operating, the skate. To accomplish these objects I form the frame

of a bar, tube or rod, of comparatively small cross section, and arrange the main portion of this bar frame, which extends between the pilot and driving wheels, substantially in line with the longitudinal center of the skate, whereby said frame may be brought into close proximity to the ground or other surface of travel without danger to any part thereof touching or coming into contact with said surface when the skate is rocked or inclined from the perpendicular.

The further points of improvement are fully set forth hereinafter.

In the accompanying drawings:—Figure 1 is a plan view, and Fig. 2 is a side elevation of a skate made according to my invention. Fig. 3 is a plan of the supporting frame detached. Figs. 4 and 5 are cross-sections taken on lines 4—4, 5—5, respectively, of Fig. 2. Fig. 6 is a plan view, and Fig. 7 a side elevation of a modified form of skate embodying certain parts of my improvements.

Referring to Figs. 1 to 5, the supporting frame A is formed of a bar, of any suitable metal or other material, the main portion a of which is T-shaped in cross-section. Each end of this T-bar a is bifurcated to straddle the wheels B, B', and serve as forks or bearings for the same. This construction is well adapted for bicycle motor skates such as described in my aforesaid more generic application for Letters Patent filed March 14, 1906 and renewed October 3, 1914, under Serial Nos. 306,073—864,943, respectively, but it will be readily understood that if two pilot or two driving wheels are used, such as shown on sheet 1 of my prior U. S. Patent, No. 706,783, dated Aug. 12, 1902, which was granted me on an application originally filed May 8, 1897 under Serial No. 635,690, the bar a would not be bifurcated at such end or ends, but would be continued straight, and provided with a journal for supporting a wheel at each side of the frame.

The bifurcated ends are bent upward so that the main bar a of the frame depends from the wheels approximately parallel with the surface of travel and with the foot-plate, and sufficiently low to enable the foot-plate to alternately approach and recede therefrom, in a substantially vertical movement, while making these reciprocations preferably below a plane through the axles of the wheels. By this arrangement the center of

gravity is kept at a very low point for safety, while the depending frame is out of the way of the foot in its movements, and the entire structure occupies no greater width than that of the foot itself. This depending bar a of the frame is in alinement with the center of the foot-plate C, and in bicycle skates, with a plane passing through the centers of the two wheels.

10 In my co-pending application Serial No. 864,943, the foot-plate is pivoted to the supporting frame substantially as shown in Fig. 2 of the present application, that is, by spacing links or levers pivoted to the foot-plate and frame so that the said levers, foot-plate and frame form together a jointed rectangle, and the foot-plate is always maintained parallel with the frame. The spacing links are preferably in the form of bell-20 cranks d and d' . The bell-cranks d are pivoted to the rear forks of the frame at a' . As shown in Figs. 1, 2 and 5, I form on the frame A an upwardly extending bracket a^2 , carrying the bearing for the pivot a^3 of the 25 front bell-crank levers d . The foot-plate C is extended at its front end beyond the point where the toe of the shoe reaches, and has a cut out portion c to permit the foot-plate to descend below the pivot bearing, as it is 30 preferable to have the bell-crank levers secured to the foot-plate in advance of the pivot a^3 , for reasons fully set forth in my said application Serial No. 864,943.

35 Rods e may connect the lower ends of the bell-cranks d , d' . The frame A is provided with lugs a^6 , see Figs. 2 and 4, against each of which bears a spring e' surrounding one of the rods e , the other end of the spring being secured to or bearing against the collar a^2 on said rod. These springs e' tend to move the rods e in the direction of the arrow, Fig. 2, and normally raise the foot-plate C. The rods e and springs e' are placed in the 45 angles beneath the projecting top sides of the T-bar a for protection, and if desired may be further protected by suitable dust-proof sheathing, although I do not ordinarily find this necessary.

50 Buffers or cushions r , secured to the supporting bar a , prevent any shock that might be caused by the foot-plate descending too rapidly and striking the bar. It is quite evident that these buffers might be placed on the under side of the foot-plate.

55 In Fig. 2, the foot-plate C, which may be stamped out of thin sheet steel or other material, is shown (in dotted lines) as provided with depending stiffening flanges c^3 , to impart to it the necessary rigidity.

60 The skate is driven by means of the internal rack teeth of the levers D engaging with lantern pinions F, which latter, though free to rotate in either direction, are connected by clutch mechanism to the driving wheel B during the forward rotation of the pin-

ions only. This driving and clutch mechanism and their mode of operation is fully set forth in my above mentioned application Serial No. 864,943 and need not therefore be more particularly described herein. In said application (and in Fig. 7 of the present application) the rack levers are shown as pivoted to the foot-plate entirely separate from the connections between the foot-plate and supporting frame. In my present invention I simplify this construction by forming each rack lever D and a rear bell-crank lever d' in one piece, as shown in Figs. 1 and 2. Therefore, the combined lever D, d' , not only forms part of the jointed rectangle or parallelogram consisting of the bar a , foot-plate C and levers d , d' , but, when the foot-plate is depressed also serves to drive the lantern pinion F, and consequently the driving wheel B, forward. It will be observed 75 that when the foot-plate C is fully depressed, in this type of my skates, its points of suspension upon the ends of the upper arms of the bell-crank levers d and d' are still above the level of the extremities of the lower arms 80 and of their tie-rods e , so that the parallelism of the foot-plate is preserved throughout its stroke.

Figs. 6 and 7 show a modification of skate to represent a centrally disposed supporting frame applied to a skate having another form of depressible foot-plate. The frame is shown as built up of small tubing, the several parts being put together substantially as a bicycle is built up. In this case the main 95 bar a^{11} carries at each end a cross-piece a^{12} , supporting tubes a^{13} . Tubes a^{14} , secured to the foot-plate C at a^{15} , are adapted to work or telescope within the tubes a^{13} . Springs a^{16} , shown in dotted lines in Fig. 7, normally 100 press the tubes a^{14} , and consequently the foot-plate C, upward. The foot-plate C' is stiffened by two longitudinally extending tubes c^{11} , shown in dotted lines in Fig. 6 and in full lines in Fig. 7, whose ends are brazed or otherwise secured within lugs c^{12} , fastened to the front and rear of the foot-plate outside of the line of the central frame tube a^{11} .

To the rear cross-piece a^{12} are secured two 115 upwardly and backwardly extending tubes a^{17} forming a forked end to the centrally disposed frame. The upper ends of the tubes a^{17} carry brackets a^{18} to support the driving wheel B. Lugs a^{19} , secured to the rear fork tubes a^{17} support the pivots of the operating rack levers D', which levers are also pivoted to the depressible foot-plate C' at c' . The forward arms of the rack levers D' are slotted, and engage with friction rollers mounted upon the foot-plate pivots c' .

To the front cross-piece a^{12} a bracket a^{21} is bolted. A single curved tube a^{22} , carried by bracket a^{21} , passes upward and over the pilot wheel B'. The fork H, carrying the pilot wheel B', is swiveled to the upper end 130

- of the tube a^{22} . This swiveling point may be directly over the axle of the wheel B' , as shown in full lines in Fig. 7, but is preferably placed somewhat in advance of a vertical line drawn from said axle, as shown in dotted lines, in order that the wheel B' may trail and guide the skate when the frame is turned to the right or to the left by the foot.
- 5 10 A guard G prevents the wheel B' from turning too far in either direction. A brake lever σ , adapted to be operated by a slight pull upon the cord or chain σ' , is mounted in operative proximity to the driving wheel B by means of a cross-piece a^{25} , secured to the vertical rear guiding posts t , that extend upward through the tubes a^{13} , a^{14} , from the frame cross-piece a^{12} , and on which the foot-plate C' is guided.
- 15 20 The foot-plates C , or C' may be provided with any suitable means for fastening the skate to the shoe, such for example, as the straps shown, or by means of adjustable metallic clamps of any well-known or desirable construction.
- 25 By providing the wheels with yielding or cushion tires, and mounting the foot-plate on yielding supports, the disagreeable effects of a frame rigidly secured to the wheels are 30 counterbalanced.
- 35 The general construction of the driving mechanism and of the skate and the manner of pivotally mounting a depressible foot-plate upon equalizing or spacing links upon a frame connecting the front and rear wheels and the mounting of the foot-plate to work below a line joining the axles of said wheels is not herein claimed but is broadly claimed, together with other features of construction 40 herein disclosed, in my co-pending application above referred to. It will therefore be understood that my present application relates merely to details of improvement upon the construction of the skate, more particularly 45 in the construction of the frame, all as more particularly specified in the claims herein, said improvements not being disclosed in the said co-pending case, which discloses the form first invented by me and 50 for which I originally first made application.
- What I claim as my invention is:
1. In a motor skate, the combination of driving and pilot wheels, a depressible foot-plate between said wheels with a centrally disposed supporting frame for said skate, extending parallel with and below the center line of said foot plate, mechanism connecting said depressible foot-plate with the driving wheel and parallel motion links between the plate and frame, substantially as set forth.
  2. In a motor skate, the combination of driving and pilot wheels, a depressible foot-plate between said wheels, with a support- 55 60 65
- ing frame for said skate extending parallel with and below the center line of said foot-plate and having one of its ends forked so as to straddle said driving wheel and parallel motion links connecting the frame and foot plate substantially as described. 70
3. In a motor skate, the combination of driving and pilot wheels, a depressible foot plate extending between said wheels, and a rigid supporting frame for said skate extending parallel with and below the center line of said foot-plate and provided at one of its ends with a fork or bifurcation adapted to straddle said driving wheel and to serve as a bearing for the same, driving levers mounted upon said fork and intermediate mechanism connecting the depressible foot-plate with said driving wheel, substantially as and for the purpose described. 75 80
4. In a motor skate, the combination of a supporting frame and a foot-plate, with spacing links pivoted to and connecting the said frame and said foot-plate, rack levers in one piece with the spacing links at one end of the skate and mechanism connecting 85 90 said rack levers with a driving wheel of the skate.
5. In a motor skate, the combination of a movable foot plate, a bar extending centrally beneath the same and connecting the forward and rear wheels of the skate, parallel motion links pivoted to said bar and to the foot plate at the rear and forward ends of the same, and driving mechanism connected with said movable foot plate. 95 100
6. In a motor skate, the combination of a centrally disposed bar T shaped in cross section, rods in the angles formed thereby, and a depressible foot-plate, with bell-crank levers pivoted to the said bar and connecting the said foot-plate with the said rods, and driving mechanism connecting said depressible foot-plate with a driving wheel of the skate. 105
7. In a motor skate, the combination of supporting wheels, a rigid central bar connecting the same but depressed below the line joining the axes of said wheels with a foot-plate mounted directly on the depressed portion of the bar adapted to reciprocate 110 through its whole range of movement above the said bar but below a plane through the axes of said wheels, and driving mechanism connecting said depressible foot-plate with one of said wheels. 115 120
8. In a motor skate, the combination of supporting wheels, and a rigid central bar connecting the same and depressed at its intermediate portion between the wheels below a line connecting the axes of said wheels with a foot-plate mounted directly on said bar and adapted to reciprocate toward and from the same, means located at the front and rear of the plate and substantially in line with the longitudinal axis of said cen- 125 130

tral bar for guiding the foot plate in its reciprocations and for maintaining its parallelism with said bar, and driving mechanism connecting said foot plate with a supporting wheel of the skate.

9. In a motor skate, the combination of a supporting frame, a foot plate, a pair of supporting links at the front and rear of the plate and each pivoted at its opposite ends 10 respectively to the plate and frame, one of said links being provided with a segmental rack, and a pinion and clutch connecting the rack and driving wheel of the skate and adapted as described to propel the skate on 15 the downward movement of the plate.

10. In a motor skate, the combination with a supporting frame, a depressible foot-plate therefor, and a driving wheel designed to be rotated by the depression of said foot 20 plate, of a combined spacing and driving lever mounted on the supporting frame and a pinion and clutch connecting said lever and driving wheel.

11. The combination of a movable foot 25 plate, a supporting frame therefor, a bar extending centrally beneath the foot plate, parallel motion links pivoted to said bar and to the foot plate at the rear and forward ends of the same and driving mechanism 30 connected with said movable foot plate, as and for the purpose described.

12. The combination of a depressible foot

plate, a supporting frame therefor, a wheel designed to be rotated by the depression of said foot plate, a combined spacing and 35 actuating lever provided with a toothed rack and a pinion and clutch coöperating with said rack and connecting said lever and wheel, as and for the purpose described.

13. In a velocipede or motor-skate, the 40 combination of a frame supporting front and rear wheels, a depressible foot-plate pivoted thereto and adapted to be reciprocated toward and from said frame, driving mechanism operated by the said foot-plate, and a 45 cushioned stop or stops between the said frame and foot-plate.

14. In a velocipede or motor-skate, a longitudinally extending frame of light yet rigid cross-section, preferably T-shaped, and provided with an upwardly projecting forked extension at its rear portion for the reception of a driving wheel, the said frame likewise being adapted to house a pair of spring-pressed parallel rods below its upper 55 surface and at either side of its longitudinal central portion, substantially as described.

Signed at New York in the county of New York and State of New York this 1st day of March A. D. 1906.

ELIAS E. RIES.
